(57) **CLAIM**

I claim the ornamental design for a massage roller, as shown and described.

DESCRIPTION

FIG. 1 is a perspective view of a massage roller, showing a first embodiment of my new design;

FIG. 2 is a left-side elevational view of FIG. 1;

FIG. 3 is a right-side elevational view of FIG. 1;

FIG. 4 is a top plan view of FIG. 1;

FIG. 5 is a bottom plan view of FIG. 1;

FIG. 6 is a front elevational view of FIG. 1;

FIG. 7 is a rear elevational view of FIG. 1;

FIG. 8 is a perspective view of a second embodiment thereof;

FIG. 9 is a left-side elevational view of FIG. 8;

FIG. 10 is a right-side elevational view of FIG. 8;

FIG. 11 is a top plan view of FIG. 8;

FIG. 12 is a bottom plan view of FIG. 8;

FIG. 13 is a front elevational view of FIG. 8; and,

FIG. 14 is a rear elevational view of FIG. 8.

The broken lines showing a cradle in FIG. 1 and handles in FIG. 2 depict environmental matter and form no part of the claimed design.
